UNITED STATES PATENT OFFICE.

PATRICK McCAFFRAY, OF PHILADELPHIA, PENNSYLVANIA, ASSIGNOR TO WILLIAM T. SMITH, OF SAME PLACE.

DESIGN FOR A CURTAIN FABRIC.

SPECIFICATION forming part of Design No. 15,765, dated February 3, 1885.

Application filed December 4, 1884. Term of patent 3½ years.

To all whom it may concern:

Be it known that I, PATRICK McCAFFRAY, (of the firm of McCAFFRAY & Co., designers,) a subject of the Queen of Great Britain, residing at Philadelphia, in the county of Philadelphia and State of Pennsylvania, have invented and produced a new and original Design for a Curtain Fabric; and I do hereby declare that the photographic print accompanying this specification conveys to any one skilled in the art a clear understanding of the same, and is sufficient to enable such person to use my invention.

The leading feature of my design consists in the representation of a peacock with folded plumage, a vase, balustrade, vines, branches, flowers, and ornamental cross-borders, as shown in the photographic print, which whole makes the ornamental design of a "dado" for a curtain fabric.
